United States Patent Office

Des. 230,657
Patented Mar. 5, 1974

230,657

MAKEUP HOLDER

Dorothy Begun, 22559 Avon Lane,
Southfield, Mich. 48075

Filed May 30, 1972, Ser. No. 258,209

Term of patent 7 years

Int. Cl. D28—03

U.S. Cl. D86—10 A

The figure is a perspective view of a makeup holder showing my new design; the unseen sides and bottom being plain and unornamented.

I claim:

The ornamental design for a makeup holder, substantially as shown and described.
